PNEUMATIC FLUID ELEVATING DEVICE

Chester D. Rubel, Wichita Falls, Tex.

Application June 12, 1930. Serial No. 460,681

46 Claims. (Cl. 103—248)

This invention relates to pumping means for oil and water wells. It has particular reference to a pneumatic pump which is operative to elevate fluid from any depth of well and in which the operation is entirely automatic. As will be apparent, either air or natural gas or a mixture of the two, or indeed substantially any other gaseous medium, can be used as the pressure medium to operate the pump; mostly for conciseness I hereinafter refer to this pressure medium as "air" or "gas".

It is well known to those skilled in this art that in drilled wells, such as oil wells, the entire pump mechanism must be confined within a relatively small diameter because of the limitations imposed by the diameters of the wells. Furthermore, deep wells require the use of considerable pressures.

The primary object of my invention is to provide a novel and improved form of pneumatic displacement pump meeting these and the other conditions encountered in the pumping of wells, and particularly in the pumping of deep drilled wells.

Other and more specific achievements will be apparent from the matter which follows herein.

An important object is the provision of a method of controlling the valve operation by the agency of alternately acting differential pressures.

Another important object is the provision in a pneumatic lift pump for oil wells, of means for creating and applying differential pressures alternately to opposite sides of an actuator element movable by reason thereof.

This application is a continuation as to all common subject matter, of my prior application Serial Number 198,193 on Pneumatic displacement pumps, filed June 11, 1927, and my prior application Serial Number 306,848, filed September 19, 1928.

With the above noted objects in view and such others as will be apparent from the description, the invention resides in the novel construction, combination and arrangement of parts herein-after illustrated and described. This specification and the accompanying drawings describe and illustrate a preferred, practical, physical embodiment of the principles of the invention, but it is obvious and it is intended that changes may be made by way of modification of structural details and the principles of the invention may be embodied in other forms without departing from the intent and scope of the invention.

Figure 1 is an elevation partly in section of an oil well installation having a pump construct-

ed in accordance with the principles of this invention.

Figure 2 is an elevation, partly in section, of an upper portion of one of the pump units.

Figure 3 is a vertical section through the intermediate portion of the unit, details of the operating mechanism being shown partly in perspective and with parts omitted for clearness.

Figure 4 is a similar view of the lower portion of the unit.

Figures 2, 3, and 4 taken together show the unit as in filling condition, with exhaust valve open and pressure inlet valve closed.

Figure 5 is a view similar to Figure 2, but in vertical section.

Figure 6 is a view similar to Figure 3, but in vertical section.

Figure 7 is a view similar to Figure 4, but in vertical section.

All of Figures 5, 6 and 7 taken together show the mechanism in oil elevating position, the pressure exhaust valve being closed and the pressure inlet valve being opened.

Figures 8, 9 and 10 are sections, partly in elevation, taken at a right angle respectively to Figures 5, 6 and 7.

Figure 11 is a section, partially in perspective, of details omitted in Figures 3, 6 and 9, and at a right angle relative thereto.

Figure 12 is a section, mainly in perspective, of details shown in Figure 10.

Figure 13 is a horizontal section on the line 13—13 of Figure 11.

Figure 14 is a horizontal section on the line 14—14 of Figure 11.

Figure 15 is a section, partly in elevation, of a detail.

Figure 16 is a vertical section of the pump of the preceding figures.

As shown in Figure 1 the pump is employed in connection with the usual string of well casing 15 having a conventional casing head 16 having outlet pipes 17 for exhaust of the pneumatic pressure medium employed. The casing head receives therethrough in the usual manner the 100 depending fluid discharge pipe line 18 which is led off at the top of the well and which line extends down through the T joint 19 having connection above the casing head with an inlet line 20 supplying the pressure medium for operating the pump and which is controllable through the valve 21. This pressure medium supply through the line 20 enters the pump string 22 in a manner to be hereinafter described.

The above described details are representative

of a general assembly which all forms of my invention may take. Inasmuch as it is possible to operate my pump through the utilization of Bradenhead gas pressure, I have illustrated in Figure 1 a means for bringing this about. This means comprises the usual installation of a Bradenhead casing 23 surrounding the usual casting 15 and having an outlet line 24 controlled through a valve 25 for communication through pipe 26 with the inlet supply line 20 to the pump. It will be obvious that with the valve 21 closed and the valve 25 open, the pressure of the Bradenhead 23 is passed through the supply line 20 to operate the pump, dispensing with the employment of external pneumatic pressure and making the entire installation an automatic self-contained and self-operative unit. In such situations the exhaust pipe 68, hereinafter referred to, may be led up to and connected to the exhaust or outlet pipe 17. As will be apparent however, and as indicated in the drawings, the pump can be operated by a pressure medium supplied otherwise than by the well itself.

The pump unit 27 as shown in Figure 1 is disposed at the bottom of the well and consists of an elongated cylindrical pump chamber closed at its bottom by a plug 28 provided with an oil inlet bore 29 communicating with the usual sand strainer 30, and which bore communicates with a tubular nipple upstanding from the plug 28 a short distance into the bottom of the pump chamber and having attached at its upper end a cage 32 within which operates a ball check valve 33.

Spaced above the top of the cage 32 is a perforated strainer plate 34 which is anchored in position by rigid connection with diametrically opposed oil discharge pipes 35 which extend vertically upward within the pump chamber being inched at their upper ends in a block 36, which block is formed with an internal passage 37 in communication with the open ends of the pipes 35 and which passage communicates at its central point with the bore 38 of an externally threaded plug 39 through means of which the block 36 is threaded into the lower end of a casting 40 to be later described in detail. This casting 40 is formed with an oil conduit 41 in communication with the bore 38 so that oil is passed upwardly through the conduit 41 and through a passageway 42 provided in the top plug or head 43 of the pump chamber. It will be observed (see Figs. 4, 7 and 10) that a space is provided, at a lower level than the outlet end of the oil inlet passage 29—31, to receive any sand that may enter the pump through the inlet passage; this is the space immediately above the plug 28 within the bottom end of the pump casing, and which entirely surrounds the nipple 31. Furthermore, the lower ends of the oil discharge pipes 35, or rather the entrances into these pipes or into at least one of them, are located in this space and at such a point therein (e. g. so low) that sand is prevented from accumulating on the floor or plug 28 of the pump chamber to such a depth as to reach the outlets from the inlet passage 29 (the openings in the valve case 32) and overflow onto the seat of the check valve 33. Unless prevented, accumulation of sand at the bottom of the pump may prevent the valve 33 for the liquid inlet passage from seating properly and thus impair the efficiency of the pump. The placement and arrangement of the discharge pipe valve 49 prevents the accumulation of sand on the seat of this valve also, as will be apparent.

The head 43 is formed with a reduced neck 44 which has attached thereto a vertical auxiliary chamber 45 concentrically disposed relative to the main chamber of the pump unit and closed at its upper end by a plug 46, which plug is provided with a central bore receiving therein the lower end of the air line pipe 22.

The oil discharge pipe line 18 extends downwardly through the pipe 22 in concentrically spaced relation passing through the plug 46 and associated at its bottom with a chamber 47 within which is disposed a cage 48 for a ball check valve 49 seated at the upper end of a tubular nipple 50 carried by a spider 51 arranged within the chamber 45 adjacent the upper end thereof and which tubular nipple is in communication with the upper end of an oil line section 52, which pipe section has communication at its lower end with the oil passage 42 in the head 43. The pipe 52 is concentrically arranged in spaced relation within and relative to the walls of the chamber 45.

From this description of the oil discharge line of the pump it is apparent that the discharge of oil from the pump chamber is from the extreme lower end of the chamber upwardly through the oil line 100 and past the check valve 49 to the oil discharge line 18, this check valve 49 being arranged and disposed in the auxiliary chamber 45 above the main chamber of the pump unit.

The pneumatic pressure medium which is preferably compressed air is supplied to the pump chamber through the pressure line 20 to the air pipe line 22 which carries the pump string by reason of its attachment in the plug 46. The pneumatic pressure medium in entering the pump chamber passes downwardly through the pipe 22 into the auxiliary chamber 45. The lower end of the chamber 45 is closed by virtue of its connection to the neck 44 on the pump head 43, but this head 43 is formed with an air passage 53 extending downwardly therethrough and communicating with an air passage 54 extending downwardly through the casting 40 and extending laterally inward at its lower end into communication with a chamber 55, which chamber is in open communication with the bottom of an upstanding valve seat 56 having an air passage 57 therethrough adapted for closing by the appropriate movement of a needle valve 58 operable vertically relative to the valve seat by means of mechanism to be later described in detail.

In order to prevent the entrance of loose scale, rust and other foreign matter into the main chamber of the pump, I provide within the auxiliary chamber 45 a vertical section of pipe 59 having communication at its lower end with the air passage 53 of the pump head 43 and which pipe is disposed in parallel relation to the pipe 52 being formed at its upper end in the shape of an annulus or ring 60 which surrounds the pipe 52 and which portion 60 is provided on its under surface with ports 61 by which air is admitted to the pipe section 59 and consequently passes downwardly through the air passage connections previously described entering through the open pressure inlet valve 58 to the interior of the main pump chamber above the body of liquid which is disposed therein in the filling cycle of the pump.

The pneumatic pressure medium is exhausted from the main pump chamber at the upper end thereof when the exhaust needle valve 62 is open. When this valve 62, which is vertically movable relative to its seat 63, is opened, the pneumatic pressure medium exhausts through the space 148

64 and through the valve seat bore 65 into a chamber 66 formed in the pump head 43, which chamber is in communication with a radial or lateral exhaust passage 67 leading therefrom to 5 a vertical exhaust pipe 68 which extends upwardly on the pump head 43 in parallel relation to the walls of the chamber 45 so that the pressure of the exhausting pneumatic medium will be directed upwardly of the pump casing thus 10 eliminating any back pressure due to lateral exhaust.

In this type of pump in the operating cycle the pump chamber is allowed to fill with oil which in ascending within the pump chamber operates 15 a member which moves at a certain point to close the pressure exhaust valve and open the pressure inlet valve. The pneumatic pressure medium then operates against the surface of the oil to force the same from the pump chamber 20 through the oil discharge line to the top of the well and when the level of liquid within the pump chamber reaches a certain point the combination of forces acting in the manner to be later explained in detail, operates to change the 25 valves so that the exhaust valve is opened and the pressure inlet valve is closed, thus permitting the pump chamber to refill with oil from the well. The means by which the valves are operated constitute a feature of this invention and 30 this valve operating means and mechanism will now be described in detail.

In the lower part of the pump chamber are provided at vertically spaced intervals a series of annular guides 69 which are rigidly attached 35 to the respective oil discharge pipes 35, which guides are centrally bored to receive therethrough in slidable relation a float which has the form of an elongated cylindrical shell 70, which shell as best shown in Figures 4 and 7, 40 has its lower end partially closed by an end plug 71 formed with a central bore 72 which is of a size sufficient to permit free entry to the interior of the shell of any gases given off from the surface of the oil rising within the pump chamber. 45 The upper end of the shell is closed by a hollow centrally upstanding neck 73 which receives therein the guide pin 74 of a hollow cylindrical mandrel 75 which mandrel has an overall length substantially three-quarters the length of the shell 50 within which it is positioned. The mandrel 75 is rigidly mounted within the pump chamber by means of a standard 76 extending downwardly from the bottom of the mandrel and passing freely through the aperture 72 in the bottom plug 71 of the shell. The bottom of the standard 55 is provided with a laterally enlarged foot portion 77 which is anchored to the strainer plate 34 by suitable means, which in the present instance comprises a securing cap 78 which engages over the foot portion 77 and which is rigidly attached to the strainer plate. As previously explained, the strainer plate 34 is rigidly mounted within the pump chamber by reason of its connection with the oil discharge pipes 35. 60 Accordingly by reason of the attachment of the mandrel to the strainer plate 34, this mandrel 75 will remain in fixed rigid position within the pump chamber.

The shell 70 is formed for free sliding movement over the mandrel, reciprocating vertically of the pump chamber. The internal diameter of the shell 70 is properly made somewhat greater than the external diameter of the mandrel 75 so that a slight clearance is provided between the walls of the shell and the mandrel, 70

the shell being at all times centered relative to the mandrel by reason of the guiding engagement of the mandrel pin 74 within the shell neck 73.

Anchored to the top of the shell neck 73 is a 80 collar 79 to which is pivoted at opposed points a pair of link levers 80 and 81. These link levers 80 and 81 extend vertically upwardly and outwardly relative to the collar 79 and have pivotal connection at their upper ends with a pair of cross levers 82 and 83 respectively, which cross levers are pivoted intermediate their ends on opposite sides of a centrally disposed mounting block 84 from the opposite side faces of which are pivotally suspended stirrups 85 and 86. The cross lever 83 is pivoted intermediate its ends to the lower end of the stirrup 85, while the cross lever 82 at the opposite side of the block is pivoted intermediate its ends to the lower end of the stirrup 86.

The opposite ends of the cross levers 82 and 83 are respectively pivoted to fixed fulcrum points 87 and 88 respectively which fulcrum points are disposed at the lower ends of anchor rods 89 and 90 depending in parallel spaced relation from the casting 40, to which casting the upper ends 100 of the anchor rods 89 and 90 are rigidly attached.

The stirrup mounting block 84 is held in position by reason of a rigid connection with the lower ends of four vertical rods 91, 92, 93 and 94 which extend upwardly from the mounting block 105 in parallel spaced relation passing freely through bores provided for that purpose in the casting 40 and which extend upwardly within the pump chamber to within a short distance below the head plug 43 thereof, as best shown in Figures 110 2 and 5.

The upper ends of these rods 91, 92, 93 and 94 terminate in a common horizontal plane and have attached thereto a bearing plate 95, which plate is centrally apertured with a bore 96 to permit passage therethrough of elements to be later described in detail.

At a point suitably arranged above the pressure inlet valve seat 56 the rods 91, 92, 93 and 94 carry in rigidly attached relation a spider plate 97, 120 which spider plate carries a depending cylinder 98 open at its bottom and adapted for relatively close fitting sliding engagement over the major body portion of the valve seat 56. The spider plate 97 is centrally apertured as at 99 to permit 125 vertical reciprocation therethrough of the stem of the needle valve 58 which controls inlet of the pneumatic pressure medium to the pump chamber.

By reason of this construction it will be apparent that as the shell 70 reciprocates vertically with respect to the mandrel 75, there will be a corresponding reciprocation of the push rods 91, 92, 93 and 94 with a consequent vertical reciprocation of the bearing plate 95 and the spider plate 135 97 with its cylinder 98, which cylinder functions as a buffer, or baffle means for the pressure medium when the pressure inlet valve is open.

The specific valve mechanism comprises a vertically elongated hollow tube 100 which passes 140 in freely slidable relation through the bore 96 of the bearing plate 95, having rigidly secured in its upper end a plug 101 formed with a peripheral flange 102 and which is provided with a central bore through which is slidably disposed the stem 145 62 of the exhaust needle valve. The needle valve 62 has at the bottom of its stem a head 103 which moves within the tube 100 being normally urged to valve stem projected position by the action of an expansion spring 104 which is housed with- 150

in the tube 100 between the valve head 103 and a partition 105 formed within the tube 100.

Rigidly attached to the lower end of the tube 100 is a valve lock 106 substantially in the form of a spool-shaped member having a laterally enlarged head 107 provided with oppositely inclined top and bottom faces as best shown in Figure 6. The stem of the needle valve 58 passes through a bore provided for that purpose 10 in the valve lock member 106 and the valve stem is provided within the tube 100 with a head 108 which cooperates with the partition 105 to receive therebetween an expansion spring 109 which normally acts against the head 108 to maintain the needle valve 58 into projected position relative to the tube 100.

The casting 40 is substantially in the form of a cylindrical plug member and parallel spaced webs 112 with a plate 111 at their tops, as best 20 illustrated in Figure 11, and it is anchored relative to the pump chamber by a connection with the pump chamber head 43. The pump head 43 has rigidly attached to the under face thereof by means of the securing bolts 110 the plate 111, which plate functions as a supporting base for the pressure exhaust valve seat 63. This plate 111 is in connection with the casting 40 by means of the diametrically opposed parallel spaced webs 112, which webs are preferably formed integral 30 with the casting 40 and the head 111 so that the elements 40, 111 and 112 may be cast together as a unit. These webs 112 are sufficiently thick in cross section to provide for the formation therethrough of the respective bores 41 and 54, forming respectively the oil discharge line 35 passage and pressure medium inlet passage previously described and they may serve as guides for the valve mechanism, e. g. specifically, the plates 95 and 97 as illustrated in Fig. 11. The casting 40 on opposite sides of the web sections 40 112 is provided with vertical bores through which the respective push rods previously described and valve lock operating rods are disposed for freely slidable movement.

Surrounding the upper portion of the valve tube 100 between the top face of the bearing plate 95 and the flange 102 of the plug 101 is arranged a coiled expansion spring 113, its respective ends abutting the bearing plate and the flange. In a similar manner a relatively heavy coiled expansion spring 114 surrounds the tube 100 between the bottom face of the bearing plate 95 and a peripheral flange 115 provided for the purpose on the valve lock member 106, respective 55 ends of this spring 114 abutting the bearing plate 95 and the flange 115.

Adjacent the laterally enlarged head 107 of the valve locking member 106 and spaced vertically on opposite sides thereof so as to be above and below the valve locking member, the webs 112 are formed with ears 116 which are positioned to receive the pivot pins of four bell crank levers arranged in sets of pairs, one set comprising the pair of levers 117 being arranged above the valve lock head 107 and the other set comprising the pair of levers 118 being disposed below the valve lock head 107. The disposition of these bell crank levers is such that in a certain position of the mechanism that is when the pressure inlet valve is open, as shown in Figure 6, the inner ends of the levers 118 will be projected beneath the lock head 107 to maintain the same in raised position. With the pressure inlet valve in closed position the parts will assume the positions as shown in Figure 3 with the inner

ends of the upper levers 117 engaged against the top face of the lock head 107, while the lower levers 118 will have been freed of their engagement against the under face of the lock head. In order to eliminate friction the respective inner 80 ends of the bell crank levers are provided with rollers for cooperating with the inclined faces of the locking head 107.

The means for actuating the bell crank levers will not be described in detail. Pivoted to the lever 83 intermediate its fixed fulcrum point 88 and its connection with the stirrup 85 is a vertically upstanding valve lock operating rod 119 which extends through a bore provided in the casting 40 for that purpose and which terminates at its upper end adjacent the spring bearing plate 95 at the top of the pump chamber. Similarly from the lever 82 there extends upwardly a second valve lock operating rod 120 which passes through the casting 40 on the opposite side and extends in parallel relation to the rod 119. Adjacent their upper ends these rods are guided by a cross arm 121 formed on the web sections 112.

Adjacent the valve lock element 106 the rod 100 119 is provided with a threaded portion 122 and in similar manner the rod 120 is provided with a threaded portion 123. Threaded over these respective threaded portions of the valve lock operating rods are respectively upper and lower 105 adjusting nuts 124 and 125. These nuts cooperate with slidable actuator elements 126 and 127 which are freely movable with respect to the rods 119 and 120. The outer ends of the bell crank levers 117 and 118 are respectively bifurcated to engage the respective push rods therebetween in freely slidable relation and in the case of the upper bell crank levers 117 slidable actuator elements 128 are mounted on the rods 119 and 120, which actuator elements are similar 110 in general construction to the actuators 126. Similarly beneath the lower set of levers 118, the rods 119 and 120 carry in slidable relation actuator elements 129 which are slidable over the rods and which are generally similar in construction to the elements 127.

The actuators 129 are normally urged into constant engagement with the bifurcated ends of the respective levers 118 through the agency of expansion springs 130 which surround the rods 125 119 and 120 between the upper face of the casting 40 and the said actuators 129. Likewise, the actuator elements 128 are urged into constant engagement with the bifurcated ends of the levers 117 through the agency of coiled expansion 130 springs 131 which surround the rods 119 and 120 between the elements 128 and the cross arm guide 121. It is obvious that by an adjustment of the nuts 124 and 125 on their respective rods, the vertical spacing of the actuator elements 126 135 and 127 may be set at any desired adjustment. This adjustment determines the timing of the valve operation and is an important feature of the present invention.

In the operation of the pump, assuming the 140 parts to be in the position as shown in Figures 2, 3 and 4 with the exhaust valve 62 open and the pressure inlet valve closed, the pump chamber will fill from the bottom with oil passing in through the strainer plug 30 and rising through 145 the check valve 33. The oil continues to pass upwardly within the pump chamber and as it rises past the strainer plate 34 above the bottom of the shell 70 a certain amount of air and gas given off from the surface of the rising oil will 150

be trapped within the shell 70 by virtue of the opening 72. As the oil continues to rise the air and gas within the shell 70 is compressed within the shell imparting a definite buoyancy thereto, the lifting action of which is assisted by the coiled spring 114 acting between the plate 95 and the flange 115, and is resisted by compression of the spring 113 acting against the upper face of the spring bearing plate 95 which is rigidly secured to the upper ends of the push rods 91, 92, 93 and 94. At this point it should be explained that under the buoyancy imparted by the trapped air within the shell, upward movement of the shell forces the links 80 and 81 upwardly and outwardly to rock the cross levers 82 and 83 upwardly with respect to their fixed fulcrums 87 and 88. At the same time through the medium of the stirrups 85, the elevating movement of the cross levers 82 and 83 is transmitted to the supporting block 84, which through its rigid connection with the push rods 91, 92, 93 and 94 causes these rods to lift, thereby lifting the spring bearing plate 95 against compression of the spring 113.

25. Inasmuch as the flange 102 on the plug 101 is maintained at this stage in a fixed position by virtue of its rigid connection with the valve tube 100, it is obvious that at some point in the continued upward movement of the shell acting as a float, the force of the spring 113 will neutralize the buoyancy of the shell and arrest the movement of the parts. This is true by reason of the fact that the lock head 107 is rigidly connected with the lower end of the tube 100 and is prevented from rising by the locking action of the upper levers 116 which are mounted on the casting webs 112 and through the medium of the rigid support afforded by these casting webs, it is obvious that the locking levers can move only to rock on their pivots. However, this check is overcome by the hydrostatic pressure of the liquid column surrounding the shell 70, acting cumulatively with the buoyancy. Due to the mandrel, a definite volume of oil is displaced within the shell, so that even though their levels may approximate the same point, the liquid column outside the shell is heavier than that inside, thus adding the power necessary to lift the actuator mechanism.

56. During the upward rocking motion of the cross levers 82 and 83 the rods 119 and 120 will be correspondingly elevated and due to the fact that the upper actuator elements 126 rest upon the lock nuts 124, under the continued upward movement of the rods 119 and 120 these actuators 126 will engage under the bifurcated ends of the levers 116, rocking the same upon their pivots so that they will be released from engagement with the lock head 107 and will assume the position as shown in Figure 6.

At the instant of this occurrence, under the expansive action of the spring 113 combined with the motive force of the shell 70, the valve tube 100 will be snapped upwardly to close the pressure exhaust valve 62 against its seat 63 and at the same time the lift thus imparted to the lock member 106 acting against the head 108 of the needle valve 58, will lift valve 58 from its seat 56 and thereby permit entry of the pneumatic pressure medium to the interior of the pump chamber.

As this pneumatic pressure medium is under considerable pressure it is necessary to provide a means for retarding the initial entry into the pump chamber in order to prevent a too rapid

building up of pressure therein. This means is provided in the cylinder 98 as air entering through the open pressure inlet valve expands within the cylinder acting upwardly against the plate 97 whereby the expansive force is resisted by the downward pull exerted on this plate 97 by the weight of the elements which are suspended therefrom by reason of its connection with the rods 91, 92, 93 and 94. Consequently, the air pressure is passed at a reduced rate from the cylinder 98 to the interior of the pump chamber above the surface of the oil confined therein by the closing of the ball check valve 33.

In this action of the mechanism downward movement of the lock head 107 is arrested by the engagement thereunder of the lock levers 118 and the air pressure builds up within the pump chamber to force the oil contained therein upwardly through the oil discharge pipes 35, passages 37 and 38, and passage 41 in the web section 112 upwardly through the passage 42 in the pump head 43 to the pipe 52 from whence it passes through the check valve 49 into the oil discharge line 18.

During the filling cycle of the pump chamber a certain amount of oil will have entered the shell 70 rising upwardly therein in the clearance space provided between the walls of the shell and the mandrel 75. Consequently although at the time of admitting the pressure medium the oil level externally of the shell 70 will be higher than the oil level within the shell, when the oil descends under the action of the pressure medium it will descend at a greater rate of speed externally of the shell 70 than within the shell due to the fact that the pneumatic pressure acting on the surface of the oil is greater than the expansive force exerted by the air and gas which is trapped in the upper portion of the shell 70.

As the oil continues to be ejected from the pump chamber the level externally of the shell 70 decreases rapidly and ultimately reaches a point at which the surface of the oil externally of the shell 70 is considerably below the level of the oil within the shell. It will be understood that at one stage the oil level both within and without the shell 70 will be at the same point and the pressures will therefore be equal. However, as the oil externally of the shell 70 drops below the oil level within the shell, the downward pressure or force exerted against the shell 70 overbalances buoyant force imparted thereto by reason of the pressure acting against the surface of the oil externally of the shell. A differential pressure is thus created which causes a downward movement of the shell 70 with considerable force thus drawing down the links 80 and 81 and rocking the cross levers 82 and 83 downwardly thereby exerting a pull on the stirrups 85 which pull is transmitted through the block 84 to the rods 91, 92, 93 and 94. This downward pull is in turn transmitted through these rods to the spring bearing plate 95 and this plate tends to move downwardly against compression of the spring 114 which surrounds the valve tube 100 between the plate 95 and the spring bearing flange 115 of the lock element 106. As the lock element is positively arrested by engagement of the levers 118 beneath the lock head 107, it is apparent that the downward movement of the elements just described will be against compression of the spring 114.

As the downward movement of the elements just described continues the rods 119 and 120 will have been correspondingly drawn down and

150

at a certain point the actuator elements 127 will engage the bifurcated ends of the bell crank levers 118 to kick the same from beneath the lock head 107, thus permitting the lock head and valve tube 100 to snap downwardly under the combined weight of the parts aided by the expansive action of the spring 114. This abrupt downward snapping movement effectively closes the pressure inlet valve 58 against its seat 56 and at the same time opens the pressure exhaust valve 62, permitting the pressure to be exhausted from the interior of the pump chamber under the inflow of oil which fills through the strainer plug 30 as in the initial filling cycle. The passage provided for exhausting the pneumatic pressure medium has already been described in detail.

As a certain percentage of the pressure medium trapped within the shell 70 may be lost by entering into solution or suspension in the oil, it may be necessary from time to time to replenish this supply without building up too great a pressure within the shell. This is effected by the provision of the mechanism shown in detail in Figure 15. This means comprises a vertical pipe 132 which is arranged externally of the shell 70 in parallel relation therewith being passed through the guides 69. At its lower end the pipe is laterally inturned and connects into the lower portion of the standard 76 which carries the mandrel 75. At this point the pipe is in open communication with a conduit or passageway 133 which is formed throughout substantially the entire length of the standard 76 and which opens adjacent the upper end of the standard into the shell 70 as best illustrated in Figure 7. At its upper end, which is disposed at a point above the highest possible liquid level within the pump chamber, the pipe 132 is capped as at 134, which cap supports a cage member 135 containing a plurality of serially arranged ball check valves 136. Adjacent the bottom of the cage or support 135 a port 137 is provided for communication to the check valves and extending from the upper end of the cage element is a conduit 138 which connects through the cap 134 to the pipe 132.

By this arrangement it will be evident that under the high pressure existing within the pump chamber during the exhausting cycle thereof, if the pressure within the shell 70 is too low, the check valves 136 will be opened, permitting a building up of pressure within the shell to the desired point. When this point has been reached the check valves 136 will of course automatically close and will not reopen until pressure within the shell has dropped below the desired point.

Regardless of the correctness of the theory of the operation of the hollow float and mandrel combination described above, the fact remains that such a combination will serve to operate the valve mechanism to admit and exhaust the pressure medium, and as will be apparent a hollow float open at or near its bottom has a desirable characteristic over entirely closed hollow floats, particularly where the air pressures are very high, in that the internal and external pressures on the former are substantially equal at substantially all times, and the mandrel seems to enable a given pump having an open hollow float to deliver a greater amount of oil per stroke than were it omitted. It is apparent too of course that valve mechanisms of the type described above are not limited in their use to pumps having the described hollow float and mandrel combination described; that is to say, while the valve mechanism described seems peculiarly suited for the hollow

float with mandrel combination, valve mechanisms of this type can be used with other float constructions where other float constructions are usable under the conditions encountered.

I claim:

1. In a pneumatically operated liquid lift pump having alternately acting pressure valve means, the method of operating the valve means which consists in periodically applying to said valve means differential pressures applied in opposite directions.

2. In a pneumatically operated liquid lift pump having alternately acting pressure inlet and exhaust valves, means for operating said valves, said means including a member positively actuated in one direction by hydraulic pressure and in an opposite direction by pneumatic pressure.

3. In a pneumatically operated liquid lift pump having alternately acting pressure supply and exhaust valves, means for operating said valves, said means including an actuator connected to said valves to actuate the same and having a surface acted upon by pneumatic pressure for positive movement of the actuator in one direction, and said actuator having a portion acted upon by hydraulic pressure for positive movement of the actuator in an opposite direction.

4. In a pneumatic pressure fluid pump, a pressure inlet valve, a pressure exhaust valve, actuator means movable to operate said valves, said actuator means having a portion responsive to pressure variation effected by differential fluid levels within the pump whereby to move said actuator means, and means for effecting and maintaining a changeable differential fluid level within the pump.

5. In a pneumatically operated liquid lift pump, valve means controlling the pressure supply and exhaust, actuator means adjacent thereto for operating said valve means, said actuator means including a plurality of connected members arranged for relatively slidable movement, latch means for holding one member in a set position, said one member being connected to said valve means to actuate the latter, means on another of the members for tripping said latch means, and a float in the liquid to be pumped controlling said another of the members.

6. In a pneumatically operated liquid lift pump, valve means controlling the pressure supply and exhaust, actuator means for operating said valve means, said actuator means including a fixed liquid displacing member, a substantially tubular member, connected to said valve means to actuate the same, open at one end and disposed over said displacement member in freely slidable relation and said tubular member and displacement member being adapted for operation while emersed in liquid lifted by the pump.

7. A pneumatically operated liquid lift pump comprising a chamber having liquid inlet and liquid outlet means, means for supplying a pneumatic pressure medium to said chamber, means for exhausting pneumatic pressure medium from said chamber, alternately acting valve means controlling the pressure medium inlet and exhaust, an actuator in said chamber and movable in one direction therein by hydrostatic pressure of liquid within the pump chamber, means on said actuator for causing movement thereof in an opposite direction under the influence of the pneumatic pressure medium supplied to said chamber, means operatively connecting said actuator and said valve mechanism, and means whereby the directional movement of said actu-

ator is controlled by the volume of liquid within the pump chamber.

8. In a pneumatically operated oil well pump, the combination with the valve mechanism controlling the supply and exhaust of the pressure medium, of means for actuating said valve mechanism in one direction under the influence of hydrostatic pressure, means for operating said valve mechanism in an opposite direction under the influence of pneumatic pressure, and means whereby the application of said pressures is automatically controlled by the volume of liquid within the pump chamber.

9. In a pneumatically operated liquid lift pump, the method of controlling the supply and exhaust of the pneumatic pressure medium which consists in effecting a differential pressure within the pump by directional movement of the liquid within the pump, and employing such differential pressure to set into operation power means controlling the supply and exhaust of the pressure medium.

10. An actuator element for pneumatically operated liquid lift pumps, comprising a fixed liquid displacement member, a hollow cylindrical shell open at one end and disposed over said displacement member in vertically slidable relation thereto, and means carried by the closed end of said shell for operating valve mechanism with which the pump may be provided.

11. In a pneumatically operated liquid lift pump, the combination with the pump chamber and pressure valve mechanism thereof, of a hollow substantially cylindrical member vertically slidable within said pump chamber and adapted for movement with its lower end disposed beneath the surface of liquid in the pump chamber, the bottom end of said cylindrical member being provided with an opening for the trapping thereof in air, and a liquid displacement body disposed within said cylindrical member and having a fixed connection with the pump chamber whereby to cause a differential pressure to exist on said cylindrical member within the pump chamber, and operating connection between the upper end of said cylindrical member and the valve mechanism of the pump.

12. In a pneumatically operated liquid lift pump having alternately acting pressure valve means, the method of operating said valve means which consists in employing differential pressures, periodically applied to said valve means in opposite directions, to produce power for operating said valve means, and controlling the periodicity by liquid levels within the pump.

13. The method of operating valves in pneumatic liquid lift pumps which consists in applying thereto power derived from an unbalance created by adding hydrostatic pressure of liquid in the pump to pressure of the pneumatic pressure medium.

14. In a pneumatically operated elongated liquid lift pump adapted to be operated in a substantially vertical position, means providing an elongated pump chamber and a liquid discharge passage leading from said chamber, valve means controlling the entrance of gas under pressure into the pump chamber to discharge liquid therefrom and controlling the exhaust of gas from the chamber, a float within the chamber operable by the liquid therein to actuate said valve means, and a plurality of rod-like members extending substantially longitudinally of and within said chamber and external of said float, to guide the float as the latter rises and falls with the liquid

level, characterized by the fact that at least one of said rod-like members is hollow and provides a lower portion of said liquid discharge passage.

15. In a pneumatically operated elongated liquid lift pump adapted to be operated in a substantially vertical position, means providing an elongated pump chamber and a liquid discharge passage leading from said chamber, valve means controlling the entrance of gas under pressure into the pump chamber to discharge liquid therefrom and controlling the exhaust of gas from the chamber, a float within the chamber operable by the liquid therein to actuate said valve means, and a plurality of rod-like members extending substantially longitudinally of and within said chamber and external of said float, to guide the float as the latter rises and falls with the liquid level, characterized by the fact that guide members for the float, to engage and more or less encircle the float, are mounted on said rod-like members.

16. In a pneumatically operated liquid lift pump, means providing a pump chamber and a liquid discharge passage leading from said chamber, valve means controlling the entrance of gas under pressure into the pump chamber to discharge liquid therefrom, spring means to operate said valve means, a member at the chamber operable by the liquid therein to put said spring means under valve-operating tension, latch means to prevent operation of said valve means by said spring means under valve-operating tension, and means to operate said latch means to release said valve means to permit operation of said valve means by said tensioned spring means.

17. In a pneumatically operated liquid lift pump, means providing a pump chamber and a liquid discharge passage leading from said chamber, valve means controlling the exhaust of gas from the pump chamber, spring means to operate said valve means, a member at the chamber operable by the liquid therein to put said spring means under valve-operating tension, latch means to prevent operation of said valve means by said spring means under valve-operating tension, and means to operate said latch means to release said valve means to permit operation of said valve means by said tensioned spring means.

18. In a pneumatically operated liquid lift pump, means providing a pump chamber and a liquid discharge passage leading from said chamber, valve means controlling the entrance of gas under pressure into the pump chamber to discharge liquid therefrom and controlling the exhaust of gas from the pump chamber, spring means to operate said valve means, a member at the chamber operable by the liquid therein to put said spring means under valve-operating tension, latch means to prevent operation of said valve means by said spring means under valve-operating tension, and means to operate said latch means to release said valve means to permit operation of said valve means by said tensioned spring means.

19. The subject of matter of claim 16, characterized by the fact that said member is a float.

20. The subject matter of claim 17, characterized by the fact that said member is a float.

21. The subject matter of claim 18, characterized by the fact that said member is a float mounted within the pump chamber.

22. In a pneumatically operated liquid lift pump, means providing a pump chamber and a liquid discharge passage leading from said

chamber, valve means controlling gas under pressure for forcing liquid from said chamber through said liquid discharge passage, a hollow float within the chamber controlling the operation of said valve means, the interior of said float being open to the chamber, and a member occupying a portion of the space within the float.

23. The subject matter of claim 22, characterized by the fact that said member occupies a portion of the space within the float that otherwise would be reached by liquid.

24. The subject matter of claim 22, characterized by the fact that said member occupies a portion of the space within the float that otherwise would be reached by liquid, and by the fact that said member is fixed in position with respect to the pump chamber.

25. In a pneumatically operated liquid lift pump, means providing a pump chamber and a liquid discharge passage leading from said chamber, valve means controlling gas under pressure for forcing liquid from said chamber through said liquid discharge passage, a float within the pump chamber to control the operation of said valve means, said float having the form of a downwardly open shell, and a member occupying a portion of the space within said shell.

26. The subject matter of claim 25, characterized by the fact that said member occupies a portion of the space within the shell above the opening thereinto, and by the fact that said member is relatively fixed in position with respect to the pump chamber.

27. In a pneumatic displacement pump, the combination with means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, and means controlled by the liquid to be pumped to control the actuation of said valve means, of a baffle for the gas under pressure entering the pump chamber through said gas inlet port.

28. The subject matter of claim 27, characterized by the fact that said baffle is a cylinder located at and receiving the gas from said gas inlet port.

29. In a pneumatic displacement pump, the combination with means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, and means responsive to the rise and fall of the liquid to be pumped to control the actuation of said valve means, of a spring tending to move said liquid-responsive means in one direction.

30. The subject matter of claim 29, characterized by the fact that said spring tends to move the liquid-responsive means in the same direction as a rise of the liquid to be pumped.

31. In a pneumatic displacement pump, the combination with means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, latch means tending to hold at least one of

said valve means in one of its positions, and a float in the liquid to be pumped to release said latch means, of a spring to assist the liquid to raise the float.

32. In a pneumatic displacement pump, the combination with means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, latch means tending to hold said valve means for said gas inlet port in passage-way closed position, and means responsive to the liquid to be pumped to release said latch, of means to assist the movement of said liquid-responsive means in the direction which brings about release of the latch.

33. In a pneumatic displacement pump, the combination with means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, latch means tending to hold said valve means for said gas inlet port in passage-way closed position, and a float in the liquid within the chamber to release said latch means as said liquid raises the float, of means tending to assist the liquid to raise the float.

34. The subject matter of claim 33, characterized by the fact that the last mentioned means is a spring.

35. In a pneumatic displacement pump, the combination of means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, latch means acting directly on said valve means to hold said valve means in a position wherein the passageway through said gas inlet port is closed and the passage-way through said exhaust port is open and also to hold said valve means in its opposite position wherein the passage-way through said gas inlet port is open and the passage-way through said exhaust port is closed, and a structure including a single member free to be actuated by the rise and fall of the liquid to be pumped to actuate said valve means to both of its said positions, characterized by the fact that said latch means are located in the path of movement of said structure for control thereby.

36. In a pneumatic displacement pump, the combination of means providing a pump chamber having gas inlet and exhaust ports and a liquid inlet port, means for supplying gas under pressure to said gas inlet port to expel the liquid, means providing a liquid-discharge passage leading from the lower portion of the pump chamber, valve means controlling said inlet and exhaust ports, latch means acting directly on said valve means to hold said valve means in a position wherein the passage-way through said gas inlet port is closed and the passage-way through said exhaust port is open and also to hold said valve means in its opposite position wherein the passage-way through said gas inlet port is open and the passage-way through said exhaust port is closed, and a structure including a float in

the liquid within the chamber, free to rise and fall as the liquid level within the pump chamber rises and falls, to actuate said valve means to both of its said positions, characterized by the fact that said latch means are located in the path of movement of said structure for control thereby.

37. The subject matter of claim 35, characterized by the fact that a spring means is interposed between said single member and said valve means, through which said single member actuates said valve means to both positions of the latter.

38. In a pneumatic displacement pump, a hollow elongated member providing the pump chamber and having an inlet for the liquid to be pumped, means providing a discharge passage for the liquid leading from the bottom portion of the chamber, a pair of spaced heads at the upper portion of the chamber, a web connecting the two heads, a seat for a gas inlet valve at one of said heads, a seat for a gas exhaust valve at the other of said heads, inlet and exhaust valve supporting means between said heads, and means below the lower of said heads, actuatable by the liquid to be pumped, to actuate the valve.

39. In a pneumatic displacement pump, a hollow elongated member providing the pump chamber and having an inlet for the liquid to be pumped, means providing a discharge passage for the liquid leading from the bottom portion of the chamber, a pair of spaced heads at the upper portion of the chamber, a web connecting the two heads, a seat for a gas inlet valve at one of said heads, a seat for a gas exhaust valve at the other of said heads, said seats facing in opposite directions, inlet and exhaust valves, a member between said heads carrying said valves, and means below the lower of said heads, actuatable by the liquid to be pumped, to actuate the valves.

40. In a pneumatic displacement pump, a hollow elongated member providing a pump chamber and having an inlet for the liquid to be pumped, means providing a discharge passage for the liquid leading from the bottom portion of the chamber, a pair of spaced heads at the upper portion of the chamber, a plurality of spaced webs connecting the two heads, a seat for a gas inlet valve at one of said heads, a seat for a gas exhaust valve at the other of said heads, gas inlet and exhaust valves, a reciprocating structure carrying said valves and guided by said webs and means below the lower head, actuatable by the liquid to be pumped, to reciprocate said structure.

41. In a pneumatically operated liquid lift pump, means providing a pump chamber and a liquid discharge passage leading from said chamber, valve means controlling the entrance of gas under pressure into the pump chamber to dis-

charge liquid therefrom, means acting on said valve means tending to operate the same, while liquid is discharging from the chamber and in which energy can be stored to operate said valve means, a member at the chamber, operable by the liquid therein, to store energy in said valve-operating means, latch means to prevent the operation of said valve means by said valve-operating means during the liquid-discharging period, and means to operate said latch means to release said valve means to permit operation of the latter by said valve-operating means.

42. In a pneumatically operated liquid lift pump, means providing a pump chamber and a liquid discharge passage leading from said chamber, valve means controlling the exhaust of gas from the pump chamber, means acting on said valve means, tending to operate the same, while liquid is entering the chamber and in which energy can be stored to operate said valve means, a member at the chamber, operable by the liquid therein, to store energy in said valve-operating means, latch means to prevent the operation of said valve means by said valve-operating means during the liquid entering period, and means to operate said latch means to release said valve means to permit operation of the latter by said valve-operating means.

43. In a pneumatically operated liquid lift pump, means providing a pump chamber and a liquid discharge passage leading from said chamber, valve means to control the entrance of gas under pressure into the pump chamber to discharge liquid therefrom and to control the exhaust of gas from the pump chamber, means acting on said valve means, tending to operate the same, during the period in which the liquid is entering the chamber and in which energy can be stored to operate said valve means, a member at the chamber, operable by the liquid therein, to store energy in said valve-operating means, latch means to prevent the operation of said valve means by said valve-operating means during the liquid-entering period, and means to operate said latch means to release said valve means to permit operation of the latter by said valve-operating means.

44. The subject matter of claim 41, characterized by the fact that said member is a float, and by the fact that said means to operate the latch means is moved by said float.

45. The subject matter of claim 42, characterized by the fact that said member is a float, and by the fact that said means to operate the latch means is moved by said float.

46. The subject matter of claim 43, characterized by the fact that said member is a float, and by the fact that said means to operate the latch means is moved by said float.

CERTIFICATE OF CORRECTION.

Patent No. 1,935,819.

November 21, 1933.

CHESTER D. RUBEL.

It is hereby certified that error appears in the printed specification of the above numbered patent requiring correction as follows: Page 2, line 39, for the syllable "in-" an-; page 4, line 85, for "not" read now; page 7, line 141, claim 19, strike out "of" first occurrence; page 8, line 106, claim 33, for "laatch" read latch; and that the said Letters Patent should be read with these corrections therein that the same may conform to the record of the case in the Patent Office.

Signed and sealed this 9th day of January, A. D. 1934.

F. M. Hopkins

(Seal)

Acting Commissioner of Patents.
